UNITED STATES PATENT OFFICE.

NORMAN F. STEVENS, OF LOS ANGELES, CALIFORNIA.

DESIGN FOR A LIGHTING FIXTURE.

Application filed May 15, 1926. Serial No. 17,731. Term of patent 3½ years.

To all whom it may concern:

Be it known that I, NORMAN F. STEVENS, a citizen of the United States, residing at Los Angeles, in the county of Los Angeles and State of California, have invented a new, original, and ornamental Design for Lighting Fixtures, of which the following is a specification, reference being had to the accompanying drawing, forming a part thereof.

In the accompanying drawings, Fig. 1 is an elevation of an ornamental lighting fixture embodying the features of my invention; Fig. 2 is a central sectional view showing one side of the fixture.

I claim:

The ornamental design for a lighting fixture substantially as shown.

NORMAN F. STEVENS.
